UNITED STATES PATENT OFFICE.

JOHN E. MEREDITH, OF BIRMINGHAM, ENGLAND, ASSIGNOR TO HOWARD MEREDITH,
OF BIRMINGHAM, ENGLAND.

LABEL.

1,414,144.

Specification of Letters Patent. Patented Apr. 25, 1922.

Application filed August 4, 1920. Serial No. 401,174.

(GRANTED UNDER THE PROVISIONS OF THE ACT OF MARCH 3, 1921, 41 STAT. L. 1313.)

To all whom it may concern:

Be it known that I, JOHN EDWARD MEREDITH, subject of the King of Great Britain, residing at Birmingham, England, have invented certain new and useful Improvements in Labels, (for which I have filed an application for patent in England on September 30, 1915,) of which the following is a specification.

10 This invention relates to labels for attaching to parcels, luggage, trees, plants and for other purposes.

The label comprises a tablet of paper, cardboard or the like carried by a sheet-15 metal backing having bent-over edges.

The metal backing of the label may be embossed with the name, trade mark, or other particulars of the sender or owner of the goods or luggage, so that it thus cannot 20 be tampered with or rendered illegible, by exposure to the weather, rough usage or otherwise, whilst the other side of the label is intended for the address of the consignee, or for the destination.

25 If desired, eyelets may be passed through the cardboard or paper and the metal backing.

In case where the label is intended to be attached to trees or plants, the metal side 30 may be embossed with the name of the grower or seller, whilst the other side may bear the name or species of tree or plant.

Figure 1 of the accompanying drawings is an elevational view showing the card-35 board or paper side of a label constructed in accordance with this invention.

Figure 2 shows the embossed metallic back of the label.

Figure 3 is a longitudinal section through 40 1 Figure 2.

Figure 4 shows a form of label which is partially adapted to be attached to trees, plants or the like, being provided with an elongated attachment tongue adapted to en-45 circle the plant, or a limb or branch thereof.

Figure 5 is an edge view of same, partly in section.

The same reference numerals indicate corresponding parts in each of the figures.

50 Referring to Figures 1 to 3 of the drawings the improved label, which will not tear or crack, comprises a piece of cardboard or paper 1 provided with a sheet-metal backing

2 upon which the name and address of the sender or consignor of the goods, or other 55 particulars, are stamped or embossed, for example, as shown in Figure 2. The backing is secured to the cardboard or paper 1 by bending its edges 3 over to the outer face of the latter, the corners of the said edges 60 being mitered or cut away as shown in Figure 1. At one or both ends of the label an eyelet 4 may be provided for attachment of the label to the goods, the said eyelet being arranged to pass through both the 65 cardboard or paper 1 and the metal backing 2, as shown in Figure 3. The embossing of the address of the consignor of the goods upon the metal backing of the label prevents same being tampered with or rendered illegible. The address of the consignee of the goods, or the destination of the goods, may 70 be written or printed upon the cardboard or paper face of the label in the usual manner.

75 Where the label is intended for attachment to plants or trees the metal backing 2 may, as shown in Figures 4 and 5, be provided with an integral attachment tongue 4 instead of eyelets, the said tongues being bent around the tree or plant and is returned and passed through a transverse slot 5 in the end of the backing, as shown by dotted lines in Figure 5. The said metal backing 2 of the label may be embossed with 80 the name and address of the grower or dealer, whilst the paper side 1 may contain 85 the name of the plant or tree.

Having fully described my invention, what I desire to claim and secure by Letters 90 Patent is:—

A label comprising a tablet of material which can be written upon, a sheet-metal backing having its edges turned over the edges of the said material, the particulars 95 of the sender embossed upon the said sheet-metal backing, and eyelets passed through both the said material and the sheet-metal backing.

In testimony whereof I have hereunto set 100 my hand in presence of two subscribing witnesses.

JOHN E. MEREDITH.

Witnesses:

W. N. SHERRETT,
